**TIPPING VALVES AND AIR SEAL FOR
DISPENSING FLUID MATERIAL**

Melville K. Gill, Clearwater, Fla., assignor to Tennessee Corporation, New York, N. Y., a corporation of New York

Application March 3, 1954, Serial No. 413,931

2 Claims. (Cl. 222—445)

The present invention relates to alternate tipping valves for dispensing fluid material of a granular, pulverulent, semi-liquid, or liquid character, and, more particularly, to an air seal discharge valve for cyclone separators and dust collectors.

Heretofore, the art has customarily made use of a discharge conduit containing a pair of superposed chambers each controlled by an individual pivoted bottom closure plate biased to closed position against the weight of material accumulated thereon, and power operated to open in timed relation so that one is always closed while the other is open. Typical examples of such devices are disclosed in U. S. Patent No. 1,414,870 to Fisher and in U. S. Patent No. 2,439,861 to Pootjes.

Prior art devices have experienced difficulties in operation, such as clogging of some kinds of material on the closure plates and their consequent failure to close properly, thus breaking the air seal and seriously hampering operation. Frequent cleaning of the closure plates is necessary, which entails costly shut downs. Although many attempts were made to overcome the foregoing difficulties and other disadvantages, none, as far as I am aware, was entirely successful when carried into practice commercially on an industrial scale.

It has now been discovered that the difficulties and disadvantages of prior art practice can be eliminated by decreasing the material contact area of the closure plates and by jarring the plates to prevent clogging of material thereon.

An object of the present invention is to provide a tipping valve having a material discharge chamber provided with a pair of center closing bottom plates whereby the material contact area of each plate is reduced with respect to the full area of material discharge.

Another object of the invention is to provide a tipping valve assembly having a material discharge passage closable by oppositely acting plates that meet centrally of the discharge passage in self-jarring forcible contact to prevent clogging of material thereon.

Other objects and advantages will become apparent from the following description taken in conjunction with the accompanying drawings, in which:

Fig. 1 is a central vertical sectional view through an alternate tipping valve assembly embodying the present invention, with the open position of the closure plates indicated in dot and dash lines;

Fig. 2 shows a front elevation of the assembly shown in Fig. 1;

Fig. 3 illustrates a side elevation of the assembly taken from the right of Fig. 2; and

Figs. 4a and 4b depict schematic illustrations of cam means for actuating the closure plates in timed sequence, the former figure showing in full lines the upper cam arm at the point of engagement with the trip cam and in dotted lines at the point of disengagement and the latter figure showing in full lines the lower cam arm at the point of engagement with the trip cam and in dotted lines at the point of disengagement.

Broadly stated, the present invention contemplates alternate tipping valves embodied in a casing for ready attachment to the bottom of a cyclone separator or the like and constituting a discharge conduit therefor. The casing houses a plurality of superposed, vertically-spaced

2

hoppers each normally closed at its bottom by a pair of oppositely acting closure plates which meet at the center of the hopper mouth in close contact to provide a seal against the passage of air. The plates are biased to closed position, and the respective pairs are mechanically opened in timed sequence such that one pair is always opened and fully closed before the next lower pair begins to open. When closing, the respective pairs of plates meet in a forcible self-jarring contact of sufficient magnitude to prevent clogging of material thereon.

In carrying the present invention into practice, it is preferred to provide the material discharge conduit as a casing 5 of rectangular cross section having at its upper end an inlet comprising a tubular neck 6 flanged for ready attachment to the bottom of a cyclone separator or other source of material supply, not shown, and at its lower end a tubular outlet 7 concentric to the inlet. The neck 6 extends downwardly within the casing to provide therein a hopper 8 normally closed at its bottom by a pair of oppositely and downwardly inclined closure plates 9 that very closely approach the complementary edge of the hopper mouth and meet at their inner ends transversely of the casing across the center of the mouth in a tight straight edge contact to provide a seal against the passage of air. It is to be observed that there is a slight clearance between the valve plates and the bottom of the hopper. The valve plates must never seat or make contact directly on the bottom edges of the hopper mouth. Such seating or contacting is prevented by the meeting engagement of the inner ends of the plates. As may be observed from Fig. 1, these plates are larger than the opening or mouth of the hopper and form an overhang to seal and prevent spillage through the slight clearance. The outer end of each plate is secured for oscillation and for rocking through an angle constituting a vertical arc by means of a shaft 10 journaled through the walls of the casing and extending outwardly thereof, and the plate is biased to closed position by a counterweight 11 adjustable along an arm 12 secured for oscillation to rock through an angle constituting a vertical arc with the rear end of the shaft.

A second hopper 13 is fixed in the casing well below the hopper 8 and in vertical registry therewith to receive material dropped therefrom when the closure plates 9 are opened. This lower hopper is normally closed at its bottom by a pair of oppositely and downwardly inclined closure plates 14 identical to the plates 9 and similarly mounted. The plates 14 very closely approach the complementary edge of the mouth of the hopper 13 leaving a slight clearance but meet at their inner ends transversely of the casing across the center of the hopper mouth in a tight straight edge contact to provide a seal against the passage of air. The outer end of each plate is secured for oscillation and for rocking through an angle constituting a vertical arc by means of a shaft 15 journaled through the walls of the casing and extending outwardly thereof, with the plate biased to closed position by a counterweight 16 adjustable along an arm 17 secured for oscillation and for rocking through an angle constituting a vertical arc with the rear end of the shaft. Material dropped from the hopper 13 when the plates 14 are opened discharges through the casing outlet 7.

The respective pairs of valve plates 9 and 14 are opened and closed in timed sequence by mechanical means comprising a driven gear or pulley 18 fixed for rotation with the rearwardly projected end of a shaft 19 that is journaled through the casing walls and extends outwardly thereof parallel to and intermediate a vertically aligned pair of the plate shafts 10 and 15. The shaft 19 has its axis in the vertical plane of the adjacent shafts 10 and 15 and carries a spur gear 20 fixed for rotation with its front end portion. This gear 20 is in constant mesh with an

identical gear 21 fixed for rotation with the front end portion of a shaft 22 that parallels the shaft 19 with its axis disposed in the vertical plane of the other pair of vertically aligned shafts 10 and 15 and intermediate the same. The shaft 22 also is journaled through the casing walls.

A cam arm 23 is fixed for oscillation and for rocking through a vertical arc with the front end on each upper valve plate shaft 10 and an identical but oppositely directed cam arm 24 is fixed for oscillation and for rocking through a vertical arc with the front end on each lower valve plate shaft 15. A revolving trip cam 25 is fixed for rotation with the front end on each of the shafts 19 and 22 for cooperative driving engagement with the cams 23 and 24 to actuate the upper and lower sets of valve plates alternately in a timed sequence and frequency determined by the speed of rotation of the spur gears 20 and 21. The cams normally are set to occupy the positions shown in Fig. 2 when both sets of upper and lower valve plates are fully closed.

In operation, the trip cams 25 revolve oppositely in the directions indicated by the arrows in Fig. 2. During the first half of their cycle they engage the cam arms 23 to rock the shafts 10 through an angle constituting a vertical arc and thereby move the upper plates 9 apart to fully opened position in which they move to and through the vertical against the bias of their counterweights. When the trip cams 25 free the arms 23 the plates swing quickly back to closed position and come together with a considerable force that jars the plates and effectively dislodges any material clogged thereon so that it collects in the apex of the V formed by the plates for discharge when they are next opened. This opening and closing of the upper plates 9 is completed before the trip cams engage the cam arms 24 to open and permit closing of the lower plates 14 in the same manner during the second half of their cycle. The engagement and disengagement of the upper cam arm 23 and the trip cam 25 is illustrated in Fig. 4a, whereas the engagement and disengagement of the lower cam arm with the trip cam is illustrated in Fig. 4b.

The self-jarring action of the dual valve plates in closing is an important feature of the present invention and a marked departure from prior art practice in which a single plate closes in full face contact against the bottom edge of a hopper mouth. A prior single valve plate seats with very little, if any, jarring, whereas in the present invention the two closure plates contact each other and do not seat directly against the edge of the hopper mouth but provide a slight clearance. As a result, the full jarring force is retained in the plates themselves and is not dissipated in the hopper. Another departure from prior art practice and a decided advantage thereover is the use of two closure plates which part in the center to open instead of a single plate which opens from one side. The employment of two plates as herein disclosed permits a shorter opening and closing cycle resulting in a more uniform flow of material. Furthermore, no material can build up on the plates. Clogging is prevented by the rapid and jolting opening and closing action of the plates, their vertical position when discharging, and the shorter contact surfaces over which the material travels in discharging.

Although the present invention has been described in conjunction with preferred embodiments, it is to be understood that modifications and variations may be resorted to without departing from the spirit and scope of the invention, as those skilled in the art will readily understand. Such modifications and variations are considered to be within the purview and scope of the invention and appended claims.

I claim:

1. An alternate tipping valve assembly comprising a vertically disposed casing constituting a conduit, a hopper located in the upper end of the casing and constituting a

material inlet therefor, a material outlet in the casing bottom, a second hopper in the casing spaced below the upper end hopper to receive material discharged therefrom, said second hopper discharging to the casing outlet, 5 a pair of downwardly and oppositely inclined valve plates mounted for rocking through a vertical arc at the bottom of each hopper and controlling material discharge therefrom, the individual plates of each pair meeting each other in tight closing contact centrally across the bottom of their respective hopper and sealing the same against passage of air therethrough when in closed position, a supporting shaft individual to each of said valve plates journaled through the casing walls and extending outwardly thereof, each plate having a fixed connection for 10 rocking through an angle with its shaft, counterweight means on an end of each plate shaft and biasing its plate to closed position, a gear shaft journaled through the casing walls intermediate and in vertical alignment with each vertical pair of the plate shafts, a pair of meshed spur gears one fixed on each gear shaft for rotation therewith, a power transmitting element keyed on one of the gear shafts, a cam arm fixed on the other end of each one of said plate shafts for rocking therewith, and a trip cam fixed on each one of said gear shafts rotative 15 therewith for alternate actuating engagement with the cam arms of its associated vertically aligned pair of the plate shafts whereby during each revolution of the trip cams the valve plates for each hopper are moved to fully open position and then closed in self-jarring contact in sequence at a predetermined frequency and speed.

2. An alternate tipping valve assembly of non-clogging character comprising a vertically disposed casing constituting a conduit, a hopper located in the upper end of the casing and constituting a material inlet therefor, a material outlet in the casing bottom, a second hopper in the casing spaced below the upper end hopper to receive material discharged therefrom, said second hopper discharging to the casing outlet, a pair of downwardly and oppositely inclined valve plates mounted for rocking through a vertical arc at the bottom of each hopper and controlling material discharge therefrom, the individual plates of each pair meeting each other in tight closing contact centrally across the bottom of their respective hopper and sealing the same against passage of air therethrough when in closed position, a slight clearance provided between said valve plates and the bottom of each hopper, an overhang on each of said plates to seal and to prevent spillage through said clearance, a supporting shaft individual to each of said valve plates journaled through the casing walls and extending outwardly thereof, each plate having a fixed connection for rocking through an angle with its shaft, counterweight means on an end of each plate shaft and biasing its plate to closed position, a gear shaft journaled through the casing walls intermediate and in vertical alignment with each vertical pair of the plate shafts, a pair of meshed spur gears one fixed on each gear shaft for rotation therewith, a power transmitting element keyed on one of the gear shafts, a cam arm fixed on the other end of each one of said plate shafts for rocking therewith, and a trip cam fixed on each one of said gear shafts rotative therewith for alternate actuating engagement with the cam arms of its associated vertically aligned pair of the plate shafts whereby during each revolution of the trip cams the valve plates for each hopper are moved to fully open position and then closed in self-jarring contact in sequence at a predetermined frequency and speed.
